UNITED STATES PATENT OFFICE

130,150

DESIGN FOR A HANDBAG

Abraham Kulick, New York, N. Y.

Application January 24, 1941, Serial No. 98,360

Term of patent 3½ years

To all whom it may concern:

Be it known that I, Abraham Kulick, a citizen of the United States of America, residing in New York city, county of New York, and State of New York, have invented a new, original, and ornamental Design for a Handbag, of which the following is a specification, reference being had to the accompanying drawings, forming part thereof, wherein,

Figure 1 is a front elevational view of a handbag showing my new design in closed position. The handle shown in this view is omitted in the remaining views for convenience of illustration.

Figure 2 is a side elevational view thereof.

Figure 3 is a rear view of the handbag shown in Figure 1.

Figure 4 is a front view of the handbag showing the front compartment in an open position.

Figure 5 is a side elevational view thereof, and

Figure 6 is an elevational view of my new design showing the rear compartment in an open position.

The dominant features of the design reside in the portions shown in full lines.

I claim:

The ornamental design for a handbag, substantially as shown and described.

ABRAHAM KULICK.
